UNITED STATES PATENT OFFICE

JOHANN WILHELM BLESCH, OF EVANSVILLE, INDIANA

CIGARETTE HOLDER

Application filed February 1, 1929. Serial No. 336,894.

The object of this invention is to provide a cigarette holder having improvements enabling the cigarette to be fed outwardly when the stub becomes very short, so that 5 the stub may be consumed almost to its extreme end; further, to provide an improved support which enables the cigarette holder to be rested on a table, desk, or other object, with the cigarette in elevated position so 10 that if the latter is burning, it will not burn the desk, table, or support; still further, to combine, in a cigarette holder, improved means for feeding the stub end of the cigarette outwardly and for supporting the 15 holder when it is laid on any object.

The embodiments of the invention are hereinafter described, set up in the appended claims, and shown in the accompanying drawings, in which:

20 Figure 1, is a side elevation showing one form of the invention, the cigarette being in the holder;

Fig. 2, is a plan view of the rest of Fig. 1;

25 Fig. 3, is a longitudinal section of a modification, the cigarette being in the holder;

Fig. 4, is a similar view, the pusher having been advanced and the cigarette removed;

Fig. 5, is a bottom view;

30 Fig. 6, is an end elevation of the construction shown in Figs. 3, 4, and 5;

Fig. 7, is a longitudinal section through the pusher of the preceding figures;

Fig. 8, is an end view thereof;

35 Fig. 9, is a longitudinal section of a modified pusher;

Fig. 10, is an end view thereof; and

Figs. 11 and 12, are front and edge views 40 of the rest of Figs. 3 to 6 inclusive.

The cigarette holder 1 may be of any desired shape and provided with the usual smoke duct or channel 2, mouthpiece 3, and chamber 4 to receive the end of the cigarette 5.

45 The chamber 4 which, in the ordinary cigarette holder, is merely utilized to receive the end of the cigarette is, in my invention, made longer than usual and in this chamber, there is located a feeder or pusher 6 which may be of tubular form, as shown in

Figs. 3, 4, 7, 8, or of channeled form, as shown in Figs. 9, 10. In the first mentioned construction, there is a port or duct 7 extending through the feeder or pusher 6 from end to end thereof so that direct communication is afforded between the cigarette 5 and the duct 2 but in the form shown in Figs. 9 and 10, instead of having a bore or duct, there is provided a channel 8 which is adapted to communicate with the duct 2. 55

The pusher or feeder 6 may be of any desired length and it is adapted to slide in the chamber 4. When pushed to the inner end of the chamber, the outer end of said chamber is adapted to accommodate the cigarette 5 and when the cigarette is for the most part consumed, the feeder or pusher 6 is then adapted to be used to push out the stub end of the cigarette so that it may be smoked instead of having to throw it away. 60

To enable the feeder or pusher 6 to be moved within its chamber 4 and also to afford a means for supporting the cigarette holder in inclined position on a desk, table or other support so that a lighted cigarette 65 will not burn the table or support, means is provided which is susceptible of modification.

For instance, in Figs. 1, 2, there is shown a support having a shank or stem 9 which extends through an elongated slot 10 in the cigarette holder and has a disc-shaped base 10. In this form, the cigarette holder 1 is supported in substantially horizontal position due to the area of the disc 10. On grasping the disc 10 the pusher or feeder 6 may be moved so that the unconsumed stub end of the cigarette 5 may be smoked, almost to its end. 80

Another form of operating and supporting means is shown in Figs. 3, 4, 5, 6, 11, 12, where the stem 9 is provided with a forked, thin base 11 which affords a finger-hold to enable the pusher to be manipulated. With this form of the support, the cigarette holder is 85 supported in inclined position when it is placed on a table, desk, or support.

I am aware that it is not necessary to employ a pusher or feeder of the length illustrated and described and that it is within the 90 95 100

spirit of the invention to provide any means whereby the support 9—10 or 9—11 may be utilized to manipulate the cigarette 5 and also used as a rest or sustaining means for holding the cigarette holder in such position on a table or other object that the lighted end of the cigarette will not come in contact with the table.

What I claim is:

- 10 1. A cigarette holder provided with an elongated chamber and a smoke duct communicating therewith and also having a longitudinally disposed slot communicating with the chamber, said chamber being adapted to receive the end of a cigarette, a pusher provided with a smoke conduit and slidably mounted in said chamber, and a combined rest and pusher-manipulator having a shank passing through said slot and engaged with the pusher and provided with a single enlarged thin piece disposed externally of the holder and lying in a plane crosswise of the length of the shank and adapted to sustain the cigarette holder in general horizontal position entirely clear of the support on which said cigarette holder is placed when not in use.
- 15 2. A cigarette holder provided with an elongated chamber and a smoke duct communicating therewith and also having a longitudinally disposed slot communicating with the chamber, said chamber being adapted to receive the end of a cigarette, a pusher provided with a smoke conduit and slidably mounted in said chamber, and a combined rest and pusher-manipulator having a shank passing through said slot and engaged with the pusher and provided with a finger-hold constituting a supporting base enabling the cigarette holder to be suspended in general horizontal position entirely clear of the support on which said cigarette holder is placed when not in use.

In testimony whereof I affix my signature.

JOHANN WILHELM BLESCH.
